D. WARREN

ROAD SIGN

Filed July 12, 1922

Fig. 1.

Fig. 2.

Inventor

Dale Warren

By *J. McAllister Thomson*

Attorney

UNITED STATES PATENT OFFICE.

DALE WARREN, OF SWEETWATER, TEXAS.

ROAD SIGN.

Application filed July 12, 1922. Serial No. 574,391.

To all whom it may concern:

Be it known that I, DALE WARREN, a citizen of the United States of America, and a resident of Sweetwater, in the county of 5 Nolan and State of Texas, have invented a new and useful Improvement in Road Signs, of which the following is a specification.

My invention relates to out-door signs, and in particular to signs placed along 10 roads and highways for the information of travelers, especially those passing in motor vehicles.

The object of my invention is to produce a compact, durable sign, difficult to destroy, 15 distinctive in its appearance, well adapted for the display of road information and advertising matter, simply constructed out of inexpensive materials, the principal item of which will, by its nature, indicate some relation to motor vehicles, and easily repaired. 20 And to this end my invention consists of the novel arrangement of parts as hereinafter described and specifically pointed out in the claims.

25 Referring now to the drawings which are a part of this specification.

Fig. 1 is an elevation of my improved sign, and

Fig. 2 is a view in cross section on line 30 2—2 of Fig. 1 looking downward.

My device consists principally of an upright post, 1, which may be kept upstanding in any well known manner, on which is placed an annular member 2, having an inwardly opening horse shoe shape for its 35 cross section, such as a tire casing, and composed mainly of fabric or other material whereby it is non-rigid. This annular fabric member 2 is disposed vertically, and attached in my preferred form, as shown, by cutting a hole at the bottom of the circle at 3, through which the post passes when it is slipped on. The opposite side of the casing 2 rests on the top of the post 1, which 40 extends within the casing, and to which it may be nailed, if desired, by nails 9, driven vertically through the casing into the top of the post.

The casing is not fastened at 3, the bottom, but left free to slide on the post 1. 45 This facilitates repairs, as hereinafter explained.

I find in practise that an annular member composed of fabric, as described, has a distinct advantage over rigid materials, in 50 that it is able to withstand assaults with fire

arms, which are frequently used to destroy road signs.

To further hold the casing 2 in position I attach to the post 1, a plurality of cleats. In 60 my preferred form as shown I have provided two cleats, 4 and 5, disposed each on the horizontal diameter of the annulus. It is obvious, however, that there can be a greater number of cleats, and that the cleats may 65 be disposed on various chords and diameters of the annulus without departing from the spirit of my invention as hereinafter defined in the claims.

These cleats are longer than the smallest 70 inside diameter of the annulus and slightly shorter than the chord of the circle traced along the inside surface of the annular member where the diameter is greatest. For convenience I shall discuss the cleats as if 75 they were lines, since obviously the ends can be shaped to conform to the arc of the circle at whatever position they are disposed.

The cleats are inserted within the casing by elongating the latter, and the post 1, 80 coming between the front and rear cleats, 4 and 5, serves to spread them axially and make them impinge tightly against the inside surface of the casing, thereby cooperating 85 with the post to hold the casing sufficiently rigid.

If a single cleat is used the post serves to a less extent to hold the casing against the cleat, and I regard a sign so constructed as within the scope of my invention as defined 90 in the claims.

I have found in practise that the annular fabric or casing so supported for display serves to attract the attention of passers by, even when no reading matter is applied to 95 the structure. And that, when the signs are placed along the road at intervals, one sign with no reading matter will attract attention to the next sign on which there is reading matter.

When so desired I place on the casing, 100 cleats and post advertising matter, road information and symbols as shown at 6, 7, and 8. I find that the casing by its nature suggests some connection with motor vehicles, and by having nothing outside the perimeter of the casing to detract attention, the interest of the observer, once attracted by the casing, becomes focused, as it were, on the matters I wish to impart.

110 The insertion of the cleats, 4 and 5, can be accomplished by pressing the casing so as to

elongate it in one direction. By reason of the casing being left free at 3, the bottom to slide on the post 1, this elongation can be effected for repair purposes without removing the casing from the post.

In describing my improved device I have explained its operation. It is obvious that many modifications may be made in my device, within the scope of my invention, as defined in the claims, and I therefore do not wish to be limited to the precise structure shown.

What I claim as new, and desire to secure by Letters Patent of the United States, is:

- 15 1. A road sign, consisting of an annular fabric whose cross section is an inwardly opening horse shoe shape, a post for support extending within the fabric member, and one or more cross members to provide bracing means, and characters imparting information disposed within the perimeter of the fabric member.
- 20 2. A road sign, consisting of an annular fabric whose cross section is an inwardly opening horse shoe shape, supporting and bracing means extending within said fabric member consisting of a post and one or more cross members, and characters imparting information disposed within the perimeter of the fabric member.
- 25 3. A road sign, consisting of an automobile tire casing, and supporting and bracing means extending within said casing consisting of a post and one or more cross members, said post passing through a hole cut in the casing.
- 30 4. A road sign, consisting of an annular fabric member whose cross section is an inwardly opening horse shoe shape, a post and one or more cross members for supporting and bracing means, said cross members extending within the fabric member, and characters imparting information disposed within the perimeter of the fabric member.
- 35 5. A road sign, consisting of an automobile tire casing, a post and one or more cross members for supporting same, said post passing through a hole cut in the casing and said cross members extending within the casing.
- 40 6. A road sign, consisting of an annular fabric member whose cross section is an inwardly opening horse shoe shape, a post for support, and one or more supporting cross members extending from the post along a chord of the annulus beyond the inside circumference thereof so as to impinge against the inside surface of the fabric member, the outside surface of the fabric member and the supporting post and cross members being adapted for the display of information.
- 45 7. A road sign, consisting of an annular fabric member whose cross section is an in-

wardly opening horse shoe shape, a post for support, and a plurality of supporting cross members separated by the post, and disposed along chords of the annulus, and extending within same beyond the inside circumference thereof, and characters imparting information disposed upon the fabric member, post or cross members.

8. A road sign, consisting of an annular fabric member, whose cross section is an inwardly opening horse shoe shape, a post for support, extending within said fabric member, and a plurality of supporting cross members, separated by the post, and disposed along chords of the annulus with their ends extending within the fabric member to touch the inside surface thereof, and characters imparting information disposed upon the fabric member, post or cross members.

9. A road sign, consisting of an annular fabric member, whose cross section is an inwardly opening horse shoe shape, a post for support, extending diametrically within said fabric member, and a plurality of supporting cross members, separated by the post, and being longer than the inside diameter of the annulus, and shorter than the outside diameter thereof, and disposed along chords of the annulus with their ends extending within the fabric member to touch the inside surface thereof, and characters imparting information disposed upon the fabric member, post, or cross members.

10. A road sign, consisting of an annular fabric member, whose cross section is an inwardly opening horse shoe shape, a post for support, extending through a hole in the bottom of the fabric member, and on whose top the fabric member rests, and a plurality of supporting cross members, separated by the post, and being longer than the inside diameter of the annulus, and shorter than the outside diameter thereof, and disposed along chords of the annulus with their ends extending within the fabric member to touch the inside surface thereof, and characters imparting information disposed upon the fabric member, post or cross members.

11. A road sign, consisting of an automobile tire casing, a post for support, extending through a hole in the bottom of the casing diametrically across the same, and on whose top the casing rests, and a pair of cleats, separated by the post, and being longer than the inside diameter of the annulus, and shorter than the outside diameter thereof, and disposed along diameters of the annulus with their ends extending within the casing to touch the inside surface thereof.

In testimony whereof I have signed the foregoing specification.

DALE WARREN.
